UNITED STATES PATENT OFFICE

JOSEPH I. STEEL, OF PORTLAND, OREGON, ASSIGNOR TO MOORE DRY KILN COMPANY OF OREGON, A CORPORATION OF OREGON

KILN FOR DRYING LUMBER AND OTHER SUBSTANCES

Application filed February 1, 1929. Serial No. 336,698.

My present invention relates to the production of improvements in the art of kiln drying and in kilns for drying lumber and other substances.

5 One important object of my invention is to effect a simplification of the duct system for employing cross-circulation of air in kilns.

10 Another object is to promote the general efficiency of kilns of the said type, due, in large measure, to employment of special means for reducing static air pressure, as well as to means for distributing the medium of circulation evenly and uniformly throughout the kiln chamber.

15 Another object of my invention, and one considered of importance not inferior to any other object proposed, is improved means for tempering the circulatory medium, that is to

20 say, qualifying the constituent elements thereof in respect to their relative proportions, and in respect to the temperature, and humidity of the medium.

25 Other objects achieved by my invention will be made apparent to one skilled in the art by careful perusal of the following specification.

30 What constitutes my invention will be hereinafter described in detail and succinctly defined in the appended claims.

35 In the accompanying drawings, wherein my invention is, with suggestion of some modifications contemplated, illustrated in the form of embodiment at present preferred,

40 Figure I is a longitudinal horizontal sectional view, partly broken away, of one of my kilns taken substantially in the plane of the fan shaft axis, and showing fans on the shaft and the fan conduit in a simple and insofar economical form of assemblage.

45 Figure II is a view similar to that of the preceding figure, showing a modification of the same by the addition of vertically disposed baffle members introduced, respectively, a short distance into the throats of the air openings of the conduit.

50 Figure III is a view similar to that of the preceding figure, showing baffle members of like form and function having supporting plates extending not only into the throats

aforesaid but also entirely across the interior of the conduit.

Figure IV is a vertical transverse section of one of my single track kilns of any preferred type of conduit, showing an air duct superposed above the fan conduit and showing one of the air intake openings therein.

Figure V is a view of a double track kiln similar to that of the preceding figure, but showing the air duct below instead of above the conduit.

Figure VI is a view similar to that shown in Figure III, but taken at right angles thereto.

Figure VII is a view similar to Figure V of a further modification of my device in respect to the air duct, showing, instead of one, two ducts on opposite sides of the fan conduit.

Figure VIII is a section on the line VIII—VIII of Figure VII.

Figure IX is a view corresponding to Figure IV, but showing a modification in respect to the location of the fan conduit in one corner of the kiln at the side of the floor instead of in the middle thereof.

Figure X is a section on the line X—X of Figure IX.

Figure XI is a section on the line XI—XI of Figure IX.

Referring to the numerals on the drawings, 1 indicates a kiln structure which may be made of any usual or other suitable and approved design, and of any material, shape, and dimensions that may be suitable and preferred for the purpose intended.

It is provided within its interior with a fan conduit 2, which may be made of any suitable and preferred dimensions and of any preferred shape in cross-section, and which extends within the kiln substantially the full length of the kiln chamber. It may be made of any preferred material, such, for example only, as concrete, wood crib, or sheet metal.

The shape in cross-section of the conduit is preferably rectangular as illustrated in the drawings. It may be, furthermore, built, as illustrated, to rest upon the bottom 3 of the kiln, and that method of construction is pre-

80

75

85

100

ferred because it is somewhat more economical than any other; but, if preferred, it may be disposed elsewhere within the kiln, and may be, for example, without substantial change in shape, disposed below the roof 4 of the kiln structure 1. It is, furthermore, contemplated that it may be disposed in any of the four corners of the kiln chamber, as indicated by the numeral 5 in Figure IX, in 10 which case its top or bottom, as the case may be, and inner side instead of its opposite sides are to be regarded as having openings as specified below.

In the method of construction of the conduit 2 which, for reason aforesaid, is that preferred, the bottom 3 of the kiln constitutes the lower wall of the conduit, and it is preferably made somewhat thicker than the other walls of the conduit as shown for example in 20 Figure V, to afford for the conduit a longitudinally disposed foundation plate 6 of augmented stability. However, if preferred, it may be made of metal and suspended above the floor of the kiln chamber specified below.

25 The conduit 2 preferably comprises, in effect, two side walls 7 and 8 extending substantially its full length. Each of the walls, which may be, as above specified, of any suitable contour or relative disposition, respectively, is made up, in effect, of a series of sections, which are aligned longitudinally in series, but are separated endwise, each from its neighbor so as to define between them openings 11 and 12.

28 At its opposite ends, the conduit 2 is provided with similar openings which are, in effect, identical with those indicated by the numerals 11 and 12 except that being terminal in respect to the conduit, they are disposed, respectively, adjacent to the end walls of the kiln.

The series of openings 11 are those in the wall 7, and the openings 12 are those provided in the wall 8, when located in opposite 45 side walls. They are, in such case, as already specified, interposed between the sections constituting the walls 7 and 8, respectively, and may be formed by disposing the opening-defining sections of one wall in staggered relationship to those of the other wall, whatever be the relative disposition of the conduit walls in which the openings are provided.

50 It has been indicated that the side walls 7 and 8 are preferably, for structural reasons that are deemed to be obvious, of vertical disposition to the foundation plate 6. Except for such structural considerations, the conduit 2 might otherwise be in the form of a cylindrical tube instead of a tube of angular cross section, and if so constructed, the openings 11 would be, in such case, provided by cutting out or omitting portions of the wall defining conduit 2 on one side, and the openings 12 would be provided by cutting 60 out or omitting portions of the wall on the

opposite side thereof. The openings 11 and 12 would, of course, be in staggered relationship one to the other, whatever be the form of the conduit, and whatever be the relative disposition of the walls in which they are 70 provided, as aforesaid.

One of the reasons which control a preference for employing a conduit 2 of rectangular shape in cross-section, is that, by aid of such mode of construction, the top plate 13 of the 75 conduit 2 may be economically incorporated with the floor 15 of the kiln chamber as well as with the side walls 7 and 8 of the said conduit.

The floor 15 may be made of any suitable 80 material preferred, and be supported by any suitable means, for example as illustrated, or by a series of cross-beams let into the side walls 17 and 18 of the kiln structure 1. The floor 15 or its equivalent is preferably employed to divide the interior of the kiln structure horizontally into three longitudinal compartments, one, the drying chamber 19 disposed above the said floor, and the other two, the heating fan-chambers 20 and 21, that are 85 disposed below it, and are separately defined by that continuous conduit wall in which the fans are included as a part.

The floor 15 does not extend entirely across the interior space of the kiln structure 1, but 90 defines between its lateral edges and the respectively adjacent side walls 17 and 18, elongated throats 22 that are, in effect, longitudinally coextensive with the length of the floor. Below the floor 15, and in operative 100 proximity to the throats 22, respectively, I provide heating means which consist preferably of coils of pipe 23 and 24 that are, respectively, in operative communication, in any usual or preferred manner, with a suitable source of heat, for example a source of steam supply, not illustrated.

The said coils may, by diminution of the spaces between the pipes thereof, be employed to effect a distribution of the circulatory medium and of the heat which they supply to the interior of the kiln by setting up a static pressure within the kiln. When so employed, the presence of pipes properly spaced apart in the coils 23 and 24, may entirely obviate the necessity of any other means for effecting distribution of the heat supplied by them and consequently of the circulating medium. In some cases, however, it may be desirable to effect a freer or less obstructed movement of the circulatory medium within the kiln, which may be accomplished by the employment of widely separated pipes in the coils 23 and 24 in combination with winged baffles to aid the action, for example, of mutually impinging currents of air derived from directly opposing fan deliveries, as are hereinafter specified.

Above the floor 15 and supported thereon by the cross-beams 16, I provide one or more 110

tracks consisting each of a pair of rails upon which travel load-supporting wheeled trucks. The number of tracks employed in any instance depends, within practicable limits, entirely upon the capacity of the kiln, and is variable accordingly, at will.

In Figure IV, a single track 25 is shown for the support of a succession of single stock-loads, one of which is indicated by the numeral 26. In Figure V, by way of example of any plurality of tracks, a double track, consisting of two pairs of rails 28 and 29, is shown as accommodating two series of stock-loads 30 and 31.

Suitable means are provided for preventing passage of the circulatory medium within the kiln around instead of through the stock loads, the circulation desired being through the spaced openings provided, in any usual or preferred method of piling the stock preferably flat piled as illustrated. Such means may consist simply of a means of partition consisting, for example, of a curtain or curtains extending between the roof 4 and the stock loads thereunder. One curtain 33 is shown in Figure IV, as employed in a single track embodiment of my invention. In Figure V, two curtains 34 and 35, for example, are shown as depending from the roof 4 in an operative proximity to the outside upper corners of the stock loads, respectively. Baffle walls 38 are provided for functioning below the stock loads with like effect as the curtains 34 and 35 above the loads.

In connection with the curtains, ventilators 36 and 37, of any usual or preferred type, are preferably provided in series distributed along the length of the roof 4, and communicating with the throats 22, respectively.

The fan conduit 2 is provided for the accommodation of a succession of fans, whereof each next adjacent pair comprises a right hand and a left hand fan. For convenience of identification, each right hand fan is indicated by the numeral 39, and each left hand fan is indicated by the numeral 40. All the fans are fixed preferably to one common shaft 41, which, if employed, is mounted at intervals in bearings 42, and which, extending through one and, if preferred, through both of the end walls of the kiln structure 1, is operatively connected at one end with a rotary motor 43 or other driving power.

The disposition of the fans in alternately reverse order on the shaft 41, for example, not only counteracts the line shaft end thrust in either direction, provided an even number of fans be employed, but in respect to their several points of location in the conduit 2, even without such provision, the action of the fans effecting suction and delivery of air, respectively, in opposite directions, accomplishes a further important result, namely, that of converting all the openings, for example the openings 11, on one side of the

conduit into air intakes and those, for example the openings 12, on the other side of the conduit into air outlets. It should in this connection, be observed that the direction of rotation of the shaft 41 is reversible at will. By this means the openings 11 may be made to function as air intakes and the openings 12 as air outlets at any given instant of time, and at the next instant, if desired, the direction of circulation in respect to said openings may be, with distinct practical advantage, reversed throughout the interior of the kiln. The openings connect with the plenum and suction corridors 11' and 12' through the throats 22 as illustrated in Figures IV and V. The designation "plenum" and "suction" corridors are relative terms and denote the condition of pressure or of suction in these areas on each side of the stock loads, depending upon the direction of circulation.

Any one of the fans is operatively mounted in the conduit 2 adjacent to sections composing, for example, the side walls 7 and 8 thereof, and which, in consequence of such disposition, extend in opposite directions substantially from the transverse axle of each one of the fans.

The operative mounting of the fans as specified in the last foregoing sentence is effected by setting each fan transversely of the conduit, so as to constitute an effective partition within the conduit 2. The fan thus constitutes in each instance a partition which is none the less effective as such because it is a movable partition, since it serves to prevent, when in rotation, the passage of air in one direction, and to compel the passage of air in the opposite direction, as effectually as if either were a solid wall. In other words, the meeting in mutual impact of opposite blasts of air or air deliveries of two directly opposing fans of substantially equal power and size, establishes in the plane in which they meet a barrier as effective as a solid wall would be. The plane in which the air deliveries meet may, therefore, be designated, to employ an accepted scientific term, a spectral partition.

This consideration should be observed in regard to the form of embodiment of my invention illustrated in Figure I of the drawings. In that figure each of the fans of each opposing pair of fans sucks in air on opposite sides of each pair and drives the air delivery of one fan against that of the fan with which it is disposed in paired relationship. Consequently, the force of delivery from one fan counteracts, to a degree of substantial exactitude, that of the fan opposed to it, and with the effect of promoting a constant lateral output of air on one side of the conduit 2 and a corresponding intake of air on the opposite side.

That the result of the meeting of opposing currents of air delivery made by oppositely

acting fans of corresponding size and power, is as effective for the making of output of air on one side of the conduit 2 as if the said delivery of the two fans were made against a physical dividing partition wall, is exemplified in the employment specified at the opposite ends of the shaft 41 of a single instead of two oppositely discharging paired fans. That is to say, there is, in such instance, at each end of the series of fans in the conduit 2 at least one fan which makes delivery of air against an end wall of the kiln, which practice demonstrates, in respect to the development of circulation, that it is as effective as if it made delivery against an air discharge from an opposing fan. It should be observed in this connection that if a series of fans comprising an even number be employed, both terminal fans of the series may, when the shaft 41 is rotated in one direction, produce suction in the openings corresponding to the openings 11 or 12 that are adjacent to the end walls. In such case, however, reversal of the direction of rotation of the shaft 41 will cause both terminal fans to discharge air delivery against the end walls, respectively.

In the method employed for installation of the fans, respectively, in a conduit 2 of rectangular shape in cross-section, each fan is mounted in a fan housing 44, which constitutes within the conduit a transverse partition that is in part a solid one. In such instance the housings 44, filled substantially as they are each by the fan enclosed therein, in combination with the sections composing the walls 7 and 8, for example, constitute what may be termed a continuous deflected or sinuous wall extending from one end to the other of the interior of the kiln. Said wall, being closed by walls at top and bottom, defines the conduit 2. If the conduit 2 be made, as it may be, in the form of a cylindrical tube, the housings 44 are unnecessary because the circular periphery of each fan may fit snugly within the cylindrical conduit without the necessity for housings which are, in effect, frames to accommodate the fans, respectively, to the rectangular shape of conduit.

With respect to the throat 22, which is substantially the same width as the space between the stock load and the kiln wall, which in some cases may form the throat, however defined, its office is to contribute in operation to the direction of flow of the atmosphere of the kiln, and it is one purpose of my invention to drive such flow, in one direction of its movement against the side wall of the kiln adjacent to the throat so that the current of flow will, by reason of its reaction against said side wall, effect passage of the air through the horizontal spaced openings provided in the stock load, with increased uniformity of circulation. When the direction of the flow of air in the kiln is reversed, the current of air in such case strikes, in like man-

ner, against the opposite side wall of the kiln and with like effect upon the loaded stock.

It may be observed upon reference to Figures IX and V, for example, that the desired deflection of a single air current resultant from two counteracting currents is accomplished, with substantially like effect, by the means illustrated in either of those figures.

As shown in Figure IX, in order to define the throat 22, the floor 15, or its equivalent, for example the edge of the stock load, should extend partly across the width of the fan conduit, and furthermore the juncture on one side wall 8 of the fan conduit with the floor 15 affords the means of deflecting the single air current aforesaid through the throat. In Figure IX, also, the side wall 8 of the fan conduit is shown as extended in the form of an obliquely disposed deflector 55.

In Figure V, however, the side wall 8 above indicated is, with like effect, extended directly to the floor 15. It will, therefore, be evident that the angle of disposition of the deflector may be varied at will within the range of ninety degrees.

In the contemplation of my invention, the end achieved by it through the employment of a directed single current produced by two counteracting currents should not be underestimated. In that regard, it should be borne in mind that the volume of such directed single current is great because of the reduction of pressure induced by the discharge against each other of two fan blasts. In a current within a duct proceeding directly from a single fan there is present not only the increased resistance of friction to air flow against the side walls of the duct with the necessity of the augmentation of power in order to overcome it, but also a necessary drift in one or the other direction of air longitudinally of the kiln, depending upon the volume of air delivery from the fan.

By the employment of a directed single current of circulation derived from counteracting discharge of two fans, which distinguishes the present invention from the art prior thereto, by the reduction of frictional resistance to air flow there is secured the additional result in connection with the employment of a series of such currents of expanding and spreading each of the currents so as to form, in the combination of said series of such currents, an overlapping circulatory flow that extends substantially the full length of the kiln. Thereby and by elimination of the drift aforesaid, the result of a greater uniformity in the drying operation of circulation is accomplished.

In respect to the effect of the reaction aforesaid of each single air current through the throat against the kiln side wall, it may be observed, upon reference to Figures IV and IX for instance, that the angle of reaction of the said current proceeding from two op-

posed fans when directed against the kiln side wall will cause reflection of said current beyond the adjacent corner of the stock load or substantially at the middle of the height 5 of the stock load, that is to say, at that point in the load where the effect of the pull of direct fan action from the opposite side of the load is feeblest. Consequently, one important 10 and distinguishing achievement of my invention is substantially to equalize circulation of air throughout the kiln, whereby the desideratum of promoting uniformity of the drying action obtained by circulation is effectuated.

In Figure IX, I show a deflector plate 55, 15 preferably connecting one side of the fan conduit to the floor 15 of the kiln. The angle at which that plate is disposed to the floor, or to the side of the load, may be varied at will through a range of ninety degrees; but 20 preferably, the floor 15, or its equivalent, extends partly across the width of the fan conduit in order to define the throat whose presence is to afford discharge of air against the adjacent kiln side wall. This deflection aids 25 in driving counteracting currents of air circulation against the adjacent side wall of the kiln when the air circulation is moving toward this adjacent side wall. The purpose of this is to provide, in either direction of circulation, means for deflecting the currents of air circulation against the adjacent side wall particularly at the corner of the flat piled 30 stock load adjacent to the throat through which the entering air passes.

35 In some cases, I prefer to employ means for directing and distributing the flow of the circulating medium in such direction as may be desired throughout the interior of the kiln.

For example of said means other than the 40 pipe coils 23 and 24 already referred to, two-wing baffle members 45 may be employed of the substantial V-shape illustrated in Figure II, with the effect of tending to distribute, with least resistance to their movement, air 45 currents towards opposite ends of the kiln.

Instead of the baffle members 45, those of the modified form indicated in Figure III by the numerals 46 may be employed with substantially the same effect. The baffle members 50 46 are two-winged like the members 45 from which they differ only by the inclusion also of a leg constituting a Y to a greater or less extent even to that of forming a transverse cross-partition 47. The cross-partition 55 47 is always present in effect, even though its actual presence is wanting, it is functionally represented by the counteractive discharges of air from the opposing fans that are shown in each one of the several Figures I, II, and 60 III.

The wings of the baffle members 45 and 46, respectively, are, by reason of having permanency of flexure, flexibly adjustable at will to different correlative angles, with the effect 65 of dividing the flow of the circulatory me-

dium of the kiln and of directing it, within determinate limitations, as may be desired.

I prefer to provide in operative communication severally with the fans of my kiln, an air duct of any suitable and desired shape, 70 extending the full length of the kiln. The duct also extends preferably through the end walls of the kiln and is adapted to take in outside air at either or both ends. Said duct may be disposed above the fans, as illustrated in Figure IV, or below them, as illustrated in Figure V, and in either of those dispositions is preferably incorporated within the structure of the conduit 2.

Other disposition of the fresh air duct may 80 be made. For example, it may be built into one or more interior corners of the kiln chamber, as indicated for example by the numeral 48 in Figure VII. In the last mentioned instance, communication between the duct and 85 the fans may be made by use of a branch intake pipe 51, one or two for each fan.

This fresh air duct may be used in connection with any type of internal fan kiln, such, for example, as a kiln for drying lumber disposed in any manner of piling, edge piling, flat edge to edge piling, or other types.

The function of the air duct is the same, irrespective of its disposition relatively to the fans, but for purposes of identification the 95 duct in Figure VII is indicated by the numeral 48, and that in Figure V is indicated by the numeral 49, and that in Figure IV by the numeral 50.

The duct, 48, 49, or 50, whichever be employed, is provided at one or both ends as preferred with a door 52, by which the admission of outside air into the duct may be at will regulated or even excluded if desired. (See 100 Figure VI).

The duct is provided at intervals, determinable by the points of location of the several fans, with air intake openings 53 of suitable capacity and of any preferred shape, one 110 for each fan, whereby air from the duct is sucked in by a fan through its opening 53 when the fan is in operation in either direction of rotation.

Each opening 53 is preferably provided 115 with means for regulating its capacity of air intake, such, for example, as a louvre or adjustable valve 54, and the width of each is preferably spanned by at least a portion of a housing rim 44 or other means to prevent air current from the fan driving into the interior of the duct instead of being sucked from it.

It has been specified above that the conduit 2 may be disposed, for example, above or below the stock loads. In that regard, diagrammatic illustration of the location of the conduit above the stock loads may be had by merely conceiving Figures IV and V or 120 IX, X, and XI, to be inverted or turned upside down, and the supports for the stock 130

loads transposed, accordingly, to the bottom 3.

The provision of an air duct with an air intake in operative communication with a 5 fan constitutes an improvement in the art of kiln drying whereby a substantially equal supply of fresh air is mechanically supplied directly to each fan by whose rotation it is commingled with the circulatory medium of 10 the kiln and the atmosphere of the kiln is kept substantially of uniform temper at all times throughout the operation of the kiln.

In view of the foregoing specification, the 15 following brief description is deemed to be a sufficient explanation of the operation of my invention.

In any form of embodiment of my invention, the kiln is charged in the usual manner with a complement of stock loads 26, for example, and the end doors of the kiln, such as 20 are common in dry kilns, are closed. Afterwards, the pipes of the coils 23 and 24 being kept properly heated, the fans are set in motion as by rotation of the shaft 41.

25 The stock loads 26, for example, being preferably of the flat piled type, and the curtain or curtains 33—35 being in effect closed, flow of the heated circulatory medium of the kiln is maintained transversely through the 30 interstices of the stock loads from the plenum corridor to the suction corridor in either direction of circulation. Substantial uniformity of the drying operation throughout the kiln is thereby maintained. A large volume of fresh air may be admitted, and uniformity of the temper of the circulatory medium in cross circulation is maintained by the aid of the door-controlled air duct communicating with the fans through the air 35 intake openings 53 thereof, respectively.

In the operation described, the ventilators 36 and 37 are employed as usual in kilns for the purpose of ventilation, those on the air exit side of the stock loads being preferably 45 utilized to the exclusion of the ventilators on the opposite side of the loads.

It has been already specified that distribution of the circulatory medium may be accomplished by a variety of means, of which 50 55 baffles constitute, by way of example, only one instance. The use of baffles is advantageous but not indispensable under some conditions, and their use makes it more practicable to obtain good results in combination with fans spaced at wide distances apart between centers. That is to say, the discreet use of baffles may be employed to economic advantage by making it possible to reduce the complement of fans necessary to kiln of given 60 size.

Moreover, baffles intermediately disposed between fans so as to deflect the respective air currents from each of the fans which contribute what may be called primary air currents 65 66 may be employed to set up auxiliary

currents generated by the meeting of the said primary currents in overlapping relationship to the conduit sections that are, as has been specified, disposed between the openings 11 and 12 in its side walls.

For similar reasons, the use of baffles renders the use of an odd number of fans in the conduit 2 practicable, efficient, in place, if preferred, of an even number of mutually counteractive fans.

What I claim is:

1. In a dry kiln, a rotary fan therein, means for defining suction and discharge sides for said fan, a housing for said fan, a fresh-air intake adjacent said housing and spaced therefrom, atmospheric communication means between said intake and both ends of said fan housing, whereby upon rotation of said fan in either direction fresh air is inspired at the suction and discharge sides, respectively, of said fan.

2. In a dry kiln, the combination of a rotary fan, a duct comprising a housing for said fan, a fresh air intake adjacent to said housing and spaced therefrom, means of atmospheric communication between said intake and both ends of said fan housing, whereby upon the rotation of said fan in either direction fresh air is inspired at the suction and discharge sides, respectively, of said fan.

3. In a dry kiln, the combination of a series of rotary fans, ducts comprising housings for said fans, respectively, a plurality of fresh air intakes adjacent to each of the said housings, respectively, and spaced therefrom, means of atmospheric communication between the said air intakes and both ends, respectively, of said fan housings whereby upon the rotation of said fans in either direction fresh air is inspired through a plurality of air intakes to the suction and discharge sides, respectively, of said fans.

4. In a dry kiln, the combination of a rotary fan, a duct comprising a housing for said fan, a fresh air intake adjacent to said housing and spaced therefrom, said intake having a louver for controlling the amount of fresh air passing therethrough, means of atmospheric communication between said intake and both ends of said fan housing whereby upon the rotation of said fan in either direction fresh air is inspired at the suction and discharge sides, respectively, of said fan.

In testimony whereof, I have hereunto set my hand.

JOSEPH I. STEEL.
